UNITED STATES PATENT OFFICE.

FRED W. BOUGHTON, OF BOSTON, MASSACHUSETTS.

SLIDE-UP TURNOVER DOOR.

1,216,202.

Specification of Letters Patent. Patented Feb. 13, 1917.

Application filed February 5, 1915. Serial No. 6,341.

To all whom it may concern:

Be it known that I, FRED W. BOUGHTON, a citizen of the United States, and a resident of Boston, in the county of Suffolk and State of Massachusetts, have invented certain new and useful Improvements in Slide-Up Turnover Doors, of which the following is a specification.

This invention relates to that class of doors, known as slide-up and turn-over doors, which are opened by raising and closed by lowering, and to the means employed in their operation; and its object is to provide a self-counterbalancing door that is of simple construction; of few parts; disposable in a small space; close fitting; a door that can be operated without the use of overhead tracks, links, or other rigid supports, other than the door frame; a door that in its closed position is out of the way and the least exposed to injury; a door furnished with simple self-closing means and self locking means; a door that can be easily operated either from the front, or from the rear; and a door that can be equipped with raising means normally inoperative, but rendered operative by engagement with a cam carried by an elevator, or by other desired means.

The invention is illustrated by the accompanying drawings, in which:

Figure 1 is a front elevation of the door; Fig. 2 is a section on line 2—2 Fig. 1;

Fig. 3 is a section on line 3—3 Fig. 1;

Fig. 4 is a section on line 4—4 Fig. 1;

Fig. 5 is a section on line 5—5 Fig. 1;

Fig. 6 is a view similar to Fig. 3 showing the door in its raised position;

Fig. 7 is a section on line 7—7 Fig. 1;

Fig. 8 is a section on line 8—8 Fig. 7;

Fig. 9 is a view similar to Fig. 7 showing one phase of the invention in its simplest form.

The door 1, adapted to fit into the frame 2, is furnished at its lower corners with forwardly projected lugs 3, wherein are journaled laterally projected wheels 4 adapted to travel up and down tracks 5, provided by the frame, and to be guided and confined in their lowermost position by the vertical floor lugs 6.

The door is raised and lowered by means of two oppositely disposed cables 7, one end of which is attached to forwardly projected lugs 8 on the upper corners of the door and the other end of which is attached to forwardly and laterally projected lugs 9 near

its lower corners. These cables 7, intermediate their ends, wind, each upon itself, around the double grooved spools 10, 10^a fixedly mounted on shaft 11 journaled in brackets 12, 12^a projected from the wall 13 and ceiling 14; said shaft 11 being furnished with gear 15 adapted to engage pinion 16 carried by sprocket wheel 17 fixedly mounted on shaft 18 slidably journaled in bracket 12 and adapted to be engaged and driven by (but normally out of engagement with) the endless chain 19 running over idlers 20, disposed above and below the door; said chain 19 being adapted to be engaged rearwardly by and travel over idlers 21 journaled on the upper and lower sides of the plunger 22, which extends rearwardly through the wall 13 and has its forward end slotted to slidably engage shafts 11 and 18 and vertically forked to straddle the sprocket wheel 17; whereby, by the forward movement of said plunger, said idlers 21 press the chain 19 into engagement with the sprocket wheel. The rearward end of plunger 22 is adapted to be engaged and actuated by the cam 24 carried by the car 25 (as indicated).

The door 1 is furnished with the counterweight 26 attached to one end of the cable 27 which passes over idler 28 and thence to the grooved spool 29, to which it is attached and upon which it winds upon itself, said spool being fixedly mounted on shaft 11.

The pinion 16 is held in engagement with gear 15 by yoke 30 centrally and oscillatingly mounted on shaft 11 and straddling said pinion 16 and spool 10 and having its arms forwardly slotted at 31 to engage the sliding shaft 18 and draw it with pinion 16 rearwardly bringing the latter into engagement with gear 15 and to maintain such engagement; the rearward end of said yoke 30 being connected by wire 32 with weight 33, which is held suspended by a second wire 34 connected with and adapted to be parted by the fusible link 35.

The door 1 is centrally and forwardly furnished with the manually operated double throw gravity latch 36, whereby it is automatically locked in closing. The door is also furnished above the latch with laterally projected hooks 37, adapted to engage the cables 7, as the door is approaching its closed position, and keep them behind the latch, as shown in Fig. 3. The diameters of the cables and widths of the grooves of the spools are so proportioned as to permit the cables to readily wind

upon themselves in the grooves and to readily unwind. The cables 7 are, each, preferably of one piece extending, when the door is in its lowered position, as shown in Figs. 5 1 and 3, from the bottom of the door to the rear of hook 37, thence to the bottom of the outer groove, thence to the bottom of the inner groove, thence wound upon itself to the top of said inner groove and thence to 10 the top of the door; the parts being all so proportioned, that, when the door is in its raised position, as shown in Fig. 6, the position of the cables is reversed, except that they are no longer engaged by hooks 37.

15 Fig. 9 illustrates the invention in its simplest form, without the plunger and the fusible link attachments, gears 15 and 16 being in engagement and shaft 18 being non-slidable; chain 19 engaging sprocket 20 wheel 17.

The operation is as follows: The door being closed and locked, as shown in Fig. 1, the operator unlatches it and pulls its upper part forward; he then pulls upon the endless chain 19 and, assisted by the counterweight 26, raises the door to its overhead position, in which position the lower end of the door engages the top of the frame 2, while the door in being raised continually 25 extends forwardly and upwardly being held in this position by the cables as they wind upon the outer grooves and unwind from the inner grooves of the spools 10, 10^a. The door is lowered by simply reversing the 30 35 pull upon the chain; the door automatically closing and being automatically locked by latch 36.

The plunger attachment, adapted to control the engagement of chain 19 and 40 sprocket wheel 17 as described, is designed particularly for use with doors leading into elevator wells; the plunger serving, when actuated by cam 24 carried by car 25, to bring the sprocket chain into engagement 45 with the sprocket wheel.

A series of doors leading into an elevator well from different floors could thus be successively controlled by a car, as it traveled up and down, and one endless chain could 50 be employed in connection therewith.

The fusible link attachment is designed to automatically disengage gears 15 and 16 and the sprocket wheel and chain, as described, in case of fire; the weight 33, upon 55 being released by the fusible link 35, depressing the rearward end of yoke 30 and raising its forward end, thereby disengaging said gears and permitting the door to automatically close.

60 The grooved spools 10, 10^a, with the cables wound thereon, each cable upon itself as described, afford means for automatically and inversely varying the leverage applied

at the bottom of the door and that applied at the top of the door, as the door is raised and lowered; thus providing for variously counterbalancing the door most advantageously in its various positions and thereby causing its effective weight to remain practically constant and the counterweight 26, 70 supported by cable 27, winding upon itself on grooved spool 29, acts similarly as an automatically varying weight according to the different positions of the door.

The door above described, when used in 75 its simplest form, as shown in Fig. 9, without the fusible link attachment, needs no counterweighting, being easily raised and lowered by a pull upon the chain and adapted, through the action of the grooved spools, to 80 remain in any position it may assume; thus having a marked advantage over all other doors of a similar character, in all of which it is necessary to employ a counterbalance equal in weight to that of the door, thus 85 doubling the weight to be supported and operated and thereby increasing the friction to be overcome and the consequent strain upon the parts.

The cables 7, arranged as described, cause 90 the upper end of the door to travel in a substantially horizontal plane, traveling forwardly at a constantly decreasing and rearwardly at a constantly increasing speed, thereby insuring its closing; the speed of 95 the bottom of the door being just the reverse, gradually increasing as the door is raised and gradually decreasing as the door closes.

It is obvious that the depth and width of 100 the grooves and the diameters of the cables may be varied as desired.

I claim:

In combination, a slide-up turn-over door; a frame therefor; a rotary shaft horizontally disposed above and forwardly of the frame; one or more double grooved spools fixedly mounted on said rotary shaft; a cable of approximately the width of the grooves attached to each spool and to the door at or near the top thereof and wound upon itself in one of said grooves in one direction, when the door is closed or lowered; another cable attached to each spool and to said door at or near the bottom thereof and wound upon itself in the other of said grooves in the opposite direction, when the door is opened or raised; and means for rotatably reciprocating the shaft, thereby raising and lowering the door.

In testimony whereof I have affixed my signature, in presence of two witnesses.

FRED W. BOUGHTON.
